UNITED STATES PATENT OFFICE.

HUGH POUND, OF PORTAGE, WISCONSIN.

SLOP-BUCKET.

SPECIFICATION forming part of Letters Patent No. 289,135, dated November 27, 1883.

Application filed October 6, 1883. (Model.)

To all whom it may concern:

Be it known that I, HUGH POUND, of Portage, in the county of Columbia and State of Wisconsin, have invented a new and Improved 5 Slop-Bucket, of which the following is a full, clear, and exact description.

The object of the invention is to improve slop-buckets by the means hereinafter described, and pointed out in the claim.

10 Reference is to be had to the accompanying drawings, forming part of this specification, in which similar letters of reference indicate corresponding parts in all the figures.

Figure 1 is a sectional elevation of my invention, taken on the line $x-x$ of Fig. 3. Fig. 15 2 is a similar view taken on the line $y-y$ of Fig. 3, and Fig. 3 is a plan view of the bucket.

A represents the body of the bucket, which may be made of any suitable size and of any 20 suitable material, and B represents the cover, which is weighted upon the under side by the centrally-placed weight C. The cover is provided at its edges with the pivots $a-a$, and the body A is provided upon the inside with the ears $b-b'$. The ear b has a plain orifice, c , made through it to receive one of the pivots a , while the ear b' is formed with the slot c' to receive the opposite pivot. Above the orifice c and the bottom of the slot c' the body A has 25 formed in it the inwardly-projecting bead D, under which the pivots $a-a$ are sprung when

the cover B is put in place, so that this bead serves both to stiffen the body A and to lock the cover B in place, so that it cannot fall out of its own accord, nor be taken out except by 35 a pull at the handle B' sufficient to spring the cover and cause the pivots $a-a$ to pass the bead. Constructed in this manner, it will be seen that, owing to the pivots a , the cover B is free to tip to the position shown in dotted 40 lines in Fig. 2, thus enabling the bucket to be filled or emptied without entirely removing the cover, and that, by means of the weight C and pivots $a-a$, the cover is made self-closing, so that the bucket is very convenient, and at 45 the same time cheap and practical.

Having thus described my invention, what I claim as new, and desire to secure by Letters Patent, is—

The bucket A, having the orificed ear b and 50 slotted ear b' upon the inside, and formed with the bead D just above the said orifice and bottom of the said slot, in combination with the cover B, provided with the pivots a , fitting in the said ears and to be sprung under the bead 55 D, substantially as and for the purposes set forth.

HUGH POUND.
